US0D1057355S

(12) **United States Design Patent** (10) **Patent No.:** **US D1,057,355 S**
(45) **Date of Patent:** **** Jan. 14, 2025**

(54) **SHIRT**

(71) Applicants: **John Serafino Craparo**, Georgetown, TX (US); **Breck L. Craparo**, Georgetown, TX (US)

(72) Inventors: **John Serafino Craparo**, Georgetown, TX (US); **Breck L. Craparo**, Georgetown, TX (US)

(**) Term: **15 Years**

(21) Appl. No.: **29/833,557**

(22) Filed: **Apr. 5, 2022**

Related U.S. Application Data

(63) Continuation-in-part of application No. 29/722,095, filed on Mar. 31, 2020, now abandoned.

(51) **LOC (15) Cl.** **02-02**

(52) **U.S. Cl.**

USPC **D2/717**; D2/840

(57) **CLAIM**

The ornamental design for a shirt, as shown and described.

DESCRIPTION

The FIGURE is a front elevation view of a shirt, showing my new design.

The rear view is plain and unornamented and forms no part of the claimed design.

The text shown in broken lines show portions of the article that form no part of the claimed design. All other broken lines show environment and form no part of the claimed design.

1 Claim, 1 Drawing Sheet
